US0D1090715S

(12) **United States Design Patent** (10) **Patent No.:** **US D1,090,715 S**
Jadeja et al. (45) **Date of Patent:** **** Aug. 26, 2025**

(54) **CURVED BUTTON PANEL DISPLAY FOR AN ELECTRONIC GAMING MACHINE**

(71) Applicant: **Aristocrat Technologies Australia Pty Limited**, North Ryde (AU)

(72) Inventors: **Rajendrasinh B. Jadeja**, Las Vegas, NV (US); **Bruce Urban**, Las Vegas, NV (US)

(73) Assignee: **Aristocrat Technologies Australia Pty Ltd.**, North Ryde (AU)

(**) Term: **15 Years**

(21) Appl. No.: **29/968,891**

(22) Filed: **Oct. 18, 2024**
